US0D1042478S

(12) **United States Design Patent** (10) **Patent No.:** **US D1,042,478 S**
(45) **Date of Patent:** **** Sep. 17, 2024**

(54) **DISPLAY PANEL OR PORTION THEREOF WITH A GRAPHICAL USER INTERFACE**

(71) Applicant: **BAE SYSTEMS plc**, London (GB)

(72) Inventors: **Antony Kershaw**, Rochester (GB);
James Austen Harrison, Rochester (GB)

(73) Assignee: **BAE SYSTEMS PLC**, London (GB)

(**) Term: **15 Years**

(21) Appl. No.: **29/795,029**

(22) Filed: **Jun. 16, 2021**

(30) **Foreign Application Priority Data**

Dec. 21, 2020 (GB) 6110637

(51) **LOC (14) Cl.** **14-04**

(52) **U.S. Cl.**

USPC **D14/485**

(57) **CLAIM**

The ornamental design for a display panel or portion thereof with a graphical user interface, as shown and described.

DESCRIPTION

The sole FIGURE illustrates a display panel or portion thereof with a graphical user interface, according to our new design.

Features enclosed by broken lines in the drawings represent environmental structure and form no part of the claimed design.

1 Claim, 1 Drawing Sheet
